UNITED STATES PATENT OFFICE.

JOHN W. HILL, OF NEW YORK, N. Y., ASSIGNOR TO J. W. DIMICK COMPANY, OF NEW YORK,
N. Y., A CORPORATION OF NEW YORK.

DESIGN FOR A RUG.

No. 39,350.

Specification for Design.

Patented June 9, 1908.

Application filed April 23, 1908. Serial No. 428,882. Term of patent 7 years.

To all whom it may concern:

Be it known that I, JOHN W. HILL, a citizen of the United States, and resident of the city, county, and State of New York, have invented a new, original, and ornamental Design for Rugs, of which the following is a specification, taken in connection with the accompanying drawings, which forms part of the same.

The figure is a plan view illustrating a quarter of a rug showing my new design.

I claim:

The ornamental design for a rug as shown.

JOHN W. HILL.
